UNITED STATES PATENT OFFICE.

GROSVENOR N. ALLEN, OF ONEIDA, NEW YORK.

DESIGN FOR A SPOON OR SIMILAR ARTICLE.

Application filed April 19, 1923. Serial No. 5,859. Term of patent 14 years.

To all whom it may concern:

Be it known that I, GROSVENOR N. ALLEN, a citizen of the United States, residing at Oneida, county of Madison, State of New York, have invented a new, original, and ornamental Design for a Spoon or Similar Article, a dominant feature residing in two medallionlike figures, one above the other, as shown in the accompanying drawing, in which—

Figure 1 is a plan view of a spoon embodying the design, and

Figures 2 and 3 are cross-sections on the lines 2—2 and 3—3 thereof.

I claim.

The ornamental design for a spoon or similar article substantially as shown and described.

In testimony whereof I have hereunto set my hand.

GROSVENOR N. ALLEN.
